[57] CLAIM

The ornamental design for suet feeder for birds, as
shown and described.

DESCRIPTION

FIG. 1 is a front perspective view of a suet feeder for
birds showing my new design;

FIG. 2 is a front elevational view thereof;

FIG. 3 is a top plan view thereof; and

FIG. 4 is a bottom plan view thereof.

It is understood that the pattern of apertures is contin-
ued uniformly throughout the bottom of the feeder as
indicated by the broken line disclosure.
